OIL BURNER

Filed July 30, 1932

FIG. 1.

UNITED STATES PATENT OFFICE

EDMUND E. MORAND, OF WESTFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS

OIL BURNER

Application filed July 30, 1932. Serial No. 626,379.

This invention relates to improvements in oil burners of the type in which a wick is mounted in a groove or channel into which the oil is fed. The so-called stove or range 5 burner of the perforated combustion tube type will serve as an example of one type of burner for which the invention is suitable.

The object of the invention is to provide an improved means for supporting the wick in 10 the oil groove of the burner in a manner such as to maintain the lower edge of the wick above the bottom of the groove.

The invention offers a very simple and inexpensive form of clip for the above purpose. A number of these clips are pressed 15 into the fuel groove of the burner at spaced points throughout its length and afford saddle-like seats on which the wick rests. The invention has the advantage that the clips are 20 readily applied to and removed from the burner and can be used with various kinds of wicks, whether of the corrugated form or otherwise.

The invention will be disclosed with reference 25 to the accompanying drawing, in which:

Fig. 1 is a plan view of the burner base; Fig. 2 is a sectional elevational view of a 30 burner taken on the line 2—2 of Fig. 1, having applied thereto the wick supporting means of my invention; and

Fig. 3 is a perspective view of one of the wick supporting clips.

Referring to the drawing; there is shown in Fig. 2 a burner of the perforated combustion tube type for the purpose of illustrating one type of burner for which the invention is adapted. However, the invention is equally applicable to any other form of burner having a fuel groove in which a wick, extending lengthwise of the groove, is to be supported in spaced relation from the bottom of such groove.

The burner comprises a base 10, having one or more oil grooves 11 therein, and a pair of 45 perforated combustion tubes 12 for each groove. Such tubes are mounted one on each side wall of each of the grooves 11 and extend upwardly therefrom to form annular combustion chambers 13, each in overlying 50 relation with a groove 11. The base 10 has

a central air passage 14 and, where there are two grooves, arcuate air passages 15 (Fig. 1) are provided between these grooves. The grooves 11 are interconnected by radial passages 16 formed in arms 17 which interconnect adjacent side walls of adjacent grooves. Oil is supplied to one of these passages by a pipe 18 (Fig. 2). A cover 19 caps the several tubes and has outlets 20 for each combustion chamber 13. This cover blocks off the upper end of the central air passage within the inner sleeve as well as the upper end of the annular air passage between the two intermediate sleeves.

In each groove a wick such as 21 is mounted. As indicated by the dot-dash lines in Fig. 1, these wicks are of endless form and they are preferably corrugated throughout their length as indicated by the small portion shown in full lines. For supporting each wick in its groove a number of clips, each of the type shown in Fig. 3, are used,—these clips being applied at spaced points along the groove.

Each clip consists of a short strip of sheet metal, preferably heat resisting steel, bent into the form shown. This clip has two straight arms 22 interconnected at their lower ends by a curved portion 23. The arms 22 diverge upwardly from the portion 23 and one of them preferably extends above the other for a purpose to be later described. This upward extension, marked 24, is preferably vertically disposed.

It will be noted that the side walls of each fuel groove 11 converge in a downward direction. The side arms 22 of the clip have the same slope and converge in the same direction and to the same degree as said walls. The length of the arms 22 is, however, less than the height of the groove. The curved part 23 spaces the arms apart sufficiently so that the clip cannot be pressed all the way down in groove 11. It can enter the groove until the upper ends of the arms 22 lie substantially flush with the upper edges of the side walls of the groove. When pressed in this far, the clip is tightly wedged in place between the side walls of groove 11 and frictionally bound thereto with the portion 23 lying above the

bottom of the groove and affording a saddle-like seat on which the wick rests. The two arms 22 being closely spaced near their lower ends centralize the lower edge of the wick in 5 the oil groove 11.

Each clip, when thus positioned, has a vertical extension 24 disposed above the top edge of the adjacent side wall of the fuel groove. When the tubes 12 are removed, these extensions 20 24 may readily be grasped by pliers and removed.

The clips have the obvious advantage of simplicity and low cost of manufacture. They are very easily applied to the fuel 15 grooves and as easily removed. Even when the clips are applied by the unskilled, they are easily and properly located. The lower blunt and unspringy end 23 of the clip can enter only to a predetermined depth in the 20 groove. Consequently, simply by pressing the clips into the groove as far as they will go, they will become properly located. The clips do not require attachment to the wick as is customarily the case. Consequently, 25 much time may be saved in assembling the parts in the burner base and the work may be done by unskilled labor.

Thus, the invention affords an improved means for supporting a wick in the fuel 30 groove of an oil burner in such a manner that the lower edge of the wick is maintained above the bottom of the groove. This is important because the space below the wick allows for the accumulation of a considerable 35 amount of residue before cleaning of the grooves is required. If the wicks rested on the bottoms of the grooves, they would soon become "cemented" thereto by the accumulation of residue. Then it would be difficult to 40 remove the wicks without distorting them or even destroying them. With the present arrangement, this does not occur and the wicks can be used over and over again. The corrugations make the wicks stronger and better 45 adapted to stand up under frequent handlings and have a longer useful life. Since the clips are not attached to the wick, the latter, after the upper edge has become unfit for further service, can be turned upside down 50 to present a fresh upper edge and secure a still further increase in the useful life of the wick.

What I claim is:

1. In an oil burner, a fuel groove having 55 side walls which converge downwardly toward the bottom thereof, a plurality of clips pressed into the groove between its side walls at spaced intervals throughout the length of the groove, each such clip comprising 60 two arms and an integral connecting portion toward and to which said arms converge, said converging arms lying against and frictionally engaging the converging side walls of said groove and said connecting portion being of greater width than the bot-

tom of the groove, whereby the depth to which the clip can be pressed into the groove is limited by said portion and the latter is spaced above the bottom of the groove, and a wick resting upon the connecting portion 70 of said several clips and between the side walls thereof.

2. In an oil burner, a fuel groove having side walls which converge downwardly toward the bottom thereof, a plurality of clips 75 pressed into the groove between its side walls at spaced intervals throughout the length of the groove, each such clip comprising two arms and an integral connecting portion toward and to which said arms converge, said converging arms lying against and frictionally engaging the converging side walls of said groove and said connecting portion being of greater width than the bottom of the groove, whereby the depth to which the clip can be pressed into the groove is limited by 80 said portion and the latter is spaced above the bottom of the groove, and a wick resting upon the connecting portion of said several clips and between the side walls thereof, 85 one of said arms being long enough to extend above the top edge of the side wall with which it is engaged.

3. In an oil burner, a fuel groove, a series 90 of roughly U-shaped spring clips pressed into said groove and having the two arms of the clip frictionally engaged with and supported by the side walls of the groove, means on each clip to limit the depth to which it can be pressed into the groove and locating 95 the bottom of the U-shaped clip at an elevation above the bottom of the groove, and a wick supported by said several clips between the arms of each clip with its lower edge resting upon the portion of each clip which connects said arms.

4. In an oil burner, a fuel groove, a series 100 of roughly U-shaped spring clips pressed into said groove and having the two arms of the clip frictionally engaged with and supported by the side walls of the groove, and a wick supported by said several clips between the arms of each clip with its lower edge resting upon the portion of each clip which connects said arms.

In testimony whereof I have affixed my signature.

EDMUND E. MORAND.
